UNITED STATES PATENT OFFICE.

MARGARET HETZEL, OF CLIFTON STATION, VIRGINIA, ASSIGNOR TO
J. E. CALDWELL & CO., OF PHILADELPHIA, PENNSYLVANIA.

DESIGN FOR A BADGE.

SPECIFICATION forming part of Design No. 21,117, dated October 13, 1891.

Application filed August 27, 1891. Serial No. 403,911. Term of patent 14 years.

To all whom it may concern:

Be it known that I, MARGARET HETZEL, a citizen of the United States, residing at Clifton Station, in the county of Fairfax and State 5 of Virginia, have invented and produced a new and original Design for a Badge, of which the following is a specification, reference being had to the accompanying drawing, forming part thereof.

10 The leading feature of my design for a badge is a star with the bust of a lady thereon, a wreath on the center of the star encircling said bust.

In the drawing, A designates a star, on the center of the face of which is a wreath B, 15 within which is a single bust C, being that of Mary Washington, the mother of George Washington. On the points of the star are circular bosses D.

I claim—

20 The design for a badge, as shown and described.

MARGARET HETZEL.
